ASH TRAY

Louis Sommerfeld, 165 W. End Ave.,
New York, N.Y. 11235

Filed Aug. 15, 1969, Ser. No. 18,715

Term of patent 7 years

Int. Cl. D27—03

U.S. Cl. D85—2

FIG. 1

FIG. 2

FIG. 1 is a side elevational view of an ash tray showing my new design, the opposite side being a mirror image of the side shown;

FIG. 2 is a top plan view;

FIG. 3 is a front elevational view;

FIG. 4 is a rear elevational view; and

FIG. 5 is a sectional view taken on the line 5—5 of FIG. 2.

I claim:

The ornamental design for an ash tray, as shown and described.
